UNITED STATES PATENT OFFICE.

DAVID PERRET, OF NEUFCHÂTEL, SWITZERLAND.

ELECTRICAL PROPELLING APPARATUS.

SPECIFICATION forming part of Letters Patent No. 658,997, dated October 2, 1900.

Application filed June 20, 1900. Serial No. 20,942. (No model.)

To all whom it may concern:

Be it known that I, DAVID PERRET, manufacturer, of Neufchâtel, Switzerland, have invented certain new and useful Improvements 5 in and Relating to Electrical Propelling Apparatus with a Double-Acting Interrupter, of which the following is a specification.

Several trials have already been made to propel a wheel by means of the armature of 10 an electromagnet, especially for the purpose of acting upon or winding up a clockwork. However, the apparatus constructed until now for that purpose have altogether the disadvantage that the most important portion 15 of the mechanism, being that portion of the same where the contact and the interruption of the electrical current takes place, shows a rapid wear and tear, which causes the mechanism to stop after having worked very little 20 time. The present invention consists in a propelling apparatus of a similar kind, in which, however, the deficiencies of the above-mentioned ones are removed by means of a double-acting interrupter. This mechanism 25 fulfils the following conditions: First, every function of the electromagnet is executed by an independent portion of the mechanism; second, the circuit is conducted through no movable parts of the apparatus, and, third, 30 the contacts are insured by pressure with a very slight gliding rotation. The first of these conditions being fulfilled, a very easy construction of the different constituent portions of the apparatus is obtained, for as the different parts of the mechanism are working 35 independently one from another their relative position may be easily determined with great exactitude, as required. The second of the above-mentioned conditions prevents 40 the mechanism being injured by oxidation of the rotary parts. The third condition prevents the quick wear and tear of the contacts and in consequence every disorder in the reciprocal position of the different parts 45 of the mechanism, which in other apparatus are produced by the perpetual gliding rotation of the contact-points. In the present apparatus this gliding has been exactly measured in such a manner as to cause the contact to take place in more than one point, 50 but with very little gliding. In consequence

the contact is insured without having the wear and tear effected by a too considerable gliding altering the distance between the different constituent parts of the apparatus. 55

The accompanying drawings represent one form of execution of the invention by way of example.

Figure 1 shows the mechanism at that moment where the attraction of the armature 60 and the interruption of the circuit at the second interrupter take place—that is to say, at that moment where the action of the accumulator begins. Fig. 2 shows the mechanism at that moment where the accumulator 65 (in the present example the spring *e*) leaves off working, whereas the second interrupter *n o* is closed and the first one *i k* is going to be closed. Fig. 3 indicates the position of the parts in which the two interrupters are closed—that is to say, that position 70 where the attraction of the armature *c* takes place by the electromagnet *d* and where the charge of the accumulator *e* takes place.

a is a ratchet-wheel fixed upon the axis of 75 any wheel of the mechanism to be rotated—for instance, on the axis of the first wheel of a clockwork, &c.

b is a click pivoted to the armature *c* of an electromagnet *d*, said armature being likewise pivoted at *w* and intended to rotate the wheel *a* tooth by tooth under the action of a spring *e*. 80

The first interrupter consists of a spring *f*, fixed to an insulated terminal *g*, bearing an 85 insulating-nose *h*, acting upon a click *x*, which gears into the teeth of the ratchet-wheel *a*. The spring *f* carries besides a contact-piece *i*, intended to be pressed against a contact-screw *k*, fixed to the insulated terminal *y* of 90 the circuit.

The second interrupter is formed by a spring *l*, fixed to an insulated terminal *v*, bearing an insulated projection *m*, which bears upon the click *b* by means of the spring *l*, the contact-piece *n* of which is intended to close the circuit of the electromagnet *d* when pressed against the setting-screw *o*, fixed to an insulated contact *p*. The setting-screws *k* and *o* may be fixed either to the insulated terminals 100 or to the respective contact-springs.

q is the battery, the circuit of which is

formed in the following manner: wire r , terminal p , contact-pieces $n o$, spring l , terminal v , wire s , coil of the electromagnet d , wire t , terminal g , spring f , contact $i k$, and through 5 the wire u back to the battery q .

The described mechanism works as follows: The parts being supposed to be in their position shown in Fig. 1, the spring of the accumulator, having been compressed by means 10 of the armature c being attracted by the electromagnet d , presses the click b down, as shown by arrow 1, causing the wheel a to rotate as indicated by the arrow 2, and consequently the click x to be lifted, whereby the 15 interruption of the contact between i and k is produced, as shown in Fig. 2. At the same time the downward movement of the click b exercises a pressure upon the spring l in the direction of arrow 3 (backward) and results 20 in pressing the contact-pieces n against the screw o , the closing of the second interrupter at the moment where the tooth h is almost at the middle of the length of the tooth of the spring-wheel by which the said spring l is 25 supported. As soon as this position is passed the click x falls upon the lowest portion of the next tooth of the wheel a , as indicated in Fig. 3, and closes at this very moment the circuit of the electromagnet, both interrupters being likewise closed. Therefore the attraction of the armature begins immediately 30 by the said electromagnet, and the click b is lifted again into the position as indicated in Fig. 1, the spring e is compressed, and the 35 interrupter $n o$ is opened again. Hereafter the working of the above-described mechanism begins anew.

The terminals y , g , v , and p are electrically insulated from the metallic mass of the 40 apparatus, and it will be clearly understood from the above description that the electrical circuit of the battery q will not pass either through the armature c or through the click b or any other movable part of the mechanism.

45 In case where the described mechanism is to act upon a clockwork the ratchet-wheel a may be fixed either to the shaft of the center wheel or of any other of the driving-wheels of the movement. The escapement of the 50 said clockwork may be any system whatever. The mechanism fulfills the first of the conditions mentioned in the beginning, the induction of the magnet being caused by a special device consisting of the spring f , carrying a contact i and operating on the click x , while the releasing of the electromagnet is caused by another device consisting of the spring l , carrying a contact n and operating on the click b . The second of the said conditions is 55 fulfilled, the current only passing through the four terminals and through the two springs f and l without passing through the pivots of any mover or of the armature or clicks b and x . Finally, also, the third condition is fulfilled, as a very small flexion of 60

65 the springs f and l takes place when the same are pressed against the contacts o and k .

Should the wires t and u be connected directly with one another, the apparatus would be able to work without the second contact 70 device—that is to say, the armature c , being pushed down by the spring e , would cause the closing of the electromagnet $n o$, and consequently the attraction of the said armature by the electro. However, this attraction would 75 immediately effect a new interruption of the circuit by means of the spring l , and by that likewise immediately the raising of the armature. The device would then play like an electrical bell—that is to say, a vibrating 80 movement of the armature would be obtained, which would be insufficient to induce the click b to rotate the ratchet-wheel a . The purpose of the combination of the two interrupters is to prevent these vibrative movements and to 85 permit each attraction of the armature to correspond to the rotation of one tooth of the ratchet-wheel a . In fact, the contact being established in $n o$, but interrupted in $i k$, Fig. 1—that is to say, the circuit being open— 90 the spring e continues to operate and to rotate the ratchet-wheel a until the tooth h escapes the tooth of the said wheel, and the moment in which this takes place may be exactly fixed by the shifting of the contact 95 g . The contact is then only formed in $i k$, whereby the action of the electromagnet is obtained. The combination of the two interrupters allows a mechanical action of the spring during that space of time that elapses 100 between the closing of the circuit in one of the interrupters and in the other one. It is this circumstance which prevents the vibrative movement observed in other similar devices.

105 Each magnetizing of the electromagnet requires a corresponding action of the motor of such a duration as to enable the ratchet-wheel to turn a tooth.

Having thus fully described my invention, 110 I claim—

In electrical propelling apparatus the combination of a ratchet-wheel and of a click pivoted to the armature of an electromagnet, the said armature being acted upon by an accumulator intended to collect the power obtained from the attraction of the said armature by the electromagnet, with two independent contact devices placed in one and the same circuit, the one of which being intended to cause the inducting of the electromagnet and consisting of two fixed insulated terminals to one of which is fixed a spring f bearing an insulated tooth h operating a click x gearing into the said ratchet-wheel, and bearing against a fixed contact-piece y the flexion of the spring alone causing a slight gliding at this contact, and the other contact device intended to stop the electromagnet, consisting also in two fixed and insulated 120 125 130

terminals to one of which is attached a spring *l* pressing by means of an insulated tooth *m* the said click into gear with the said ratchet-wheel, while the other terminal forms the fixed contact-piece, against which the flexion of the spring *l* alone causes the slight gliding at the contact-point, substantially as and for the purpose specified.

In testimony that I claim the foregoing as my invention I have signed my name in presence of two subscribing witnesses.

DAVID PERRET.
